PROCESS FOR THE SOLVENT EXTRACTION OF AROMATICS FROM HYDROCARBON MIXTURES

Glenn R. Brown, Jr., Cleveland, and Harold A. Strecker, Bedford, Ohio, and Richard R. Crawford, Buffalo, N. Y., assignors to The Standard Oil Company, Cleveland, Ohio, a corporation of Ohio

Application June 1, 1956, Serial No. 588,836

7 Claims. (Cl. 208—323)

The present invention relates to an improved process for the extraction and recovery of an aromatic enriched hydrocarbon fraction from mixtures of aromatic and other hydrocarbons. It is especially adapted to be used in connection with hydrocarbon mixtures containing benzene, toluene, xylenes, ethylbenzene and higher homologues.

While the method of this invention is broadly applicable to any liquid hydrocarbon mixture containing appreciable amounts of aromatic compounds, it is especially suited to the treatment of hydrocarbon mixtures produced by the catalytic reforming of heavy naphtha, a mixture of paraffinic and naphthenic hydrocarbons boiling in the range of about 200° F. to about 400° F. The unleaded F-1 octane number of hydrocarbon stocks produced by catalytic reforming may vary between about 80 and 95, but a stock which is particularly suited to the practice of this invention has an unleaded octane number of about 85.

Catalytic reforming is a process which is today widely practiced in the petroleum industry and the object of that process is the production of aromatic compounds from naphthenic and other non-aromatic ingredients of heavy naphtha by a combination of isomerization and dehydrogenation. The catalytic reforming processes are usually conducted at an elevated temperature and pressure in the presence of a catalyst in a hydrogen atmosphere. One type of catalyst which is widely used in such processes contains platinum as the principal active ingredient. The product of a catalytic reforming operation is characterized by an octane number in the range of about 80 to 95 and it is suitable for use in motor gasoline.

Under some circumstances, it is desired to separate a fraction enriched in aromatics from the product of a catalytic reforming operation. The catalytic reforming operation does not completely convert the heavy naphtha feed into aromatic compounds under the usual operating conditions and the aromatics which are produced by the reforming operation are diluted by the presence in the product of paraffinic and other non-aromatic compounds. Accordingly, when the object of the catalytic reforming process is the production of relatively pure aromatic compounds, it is necessary to concentrate the aromatic portion of the product of the catalytic reforming operation. A similar situation prevails when the product of the cat-

alytic reforming operation is to be used as a motor fuel and only the highest octane ingredients of the product are desired.

The art has suggested a number of methods for improving the octane number of naphthas in general, and in particular, the products of the catalytic reforming operation. A number of these methods involve the solvent extraction of the naphtha or catalytic reformate whereby the aromatic content of the stock treated is selectively removed and separated from the non-aromatic ingredients.

One such process which has been suggested by the prior art is described in U. S. Patent No. 2,302,383 to Stratford. This patent describes a process in which naphtha is upgraded by solvent extraction with dihydric alcohols having at least one ether group, as for example, diethylene glycol, triethylene glycol, and tetraethylene glycol.

The dihydric glycols, while they possess a very high degree of selectivity in separating aromatic compounds from paraffinic compounds, have the disadvantage that aromatic hydrocarbons are not readily soluble therein and consequently considerable quantities of the glycols must be employed in order to effect an appreciable separation of the aromatic compounds. The high solvent to oil ratio which is required in processes employing dihydric glycols makes these processes expensive, both as to capital costs and operating costs. The capital costs are expensive because of the large equipment that is necessary to accommodate the required volumes of the solvent and oil. The operating costs are expensive because the separation of the solvent from the oil after extraction is usually accomplished by distillation and the large quantities of solvent employed in such processes necessitate the consumption of large quantities of heat to effect the separation of the solvent from the enriched oiling.

Another process which has been suggested by the prior art is described in U. S. Patents Nos. 2,337,732 and 2,364,517 to Burk. Among the solvents suggested by Burk for use in his process are certain amine compounds. Among the hydroxyamines disclosed is phenyl ethanol amine. Hydroxyamines have a disadvantage when employed as a solvent in the extraction of light hydrocarbon distillates in that they do not possess a great degree of selectivity for aromatic hydrocarbons. Consequently, a practical increase in the aromatic content of a hydrocarbon mixture cannot be obtained with hydroxyamines under practical operating conditions.

Accordingly, one of the objects of this invention is to provide an improved process for the production of an aromatic enriched fraction from a hydrocarbon mixture containing aromatics which avoids the disadvantages of the prior art.

It is another object of this invention to provide a solvent extraction process for the recovery of aromatics from hydrocarbon mixtures which does not require high solvent to oil ratios.

Still another object of this invention is to provide a

process for the production of a high octane gasoline from a lower octane product of a catalytic reforming operation. More especially, it is an object of this invention to provide a process whereby a gasoline having an octane number of 100 or above may be obtained from a gasoline having an octane number below 90, and in particular, to provide a solvent extraction process whereby at least a 10% yield of at least 100 octane gasoline may be obtained from a gasoline having an octane number of at least 85.

In order to facilitate an understanding of this invention, a patent drawing is attached hereto in which Figure 1 is a schematic flow diagram illustrating the method of this invention, and Figure 2 is a graph illustrating the improved results obtainable by means of this invention.

In brief, this invention is a process comprising the steps of extracting a liquid hydrocarbon mixture containing an appreciable quantity of aromatic compounds under conditions which will produce a separate raffinate and extract consisting of a solvent-oil mixture with a solvent consisting essentially of a mixture of diethylene glycol and phenyl ethanol amine, and the step of separating an aromatic enriched hydrocarbon mixture from said solvent-oil mixture.

The improved results obtainable by the method of this invention are principally attributable to the solvent employed. As pointed out above, the solvent is a mixture consisting essentially of phenyl ethanol amine and diethylene glycol. However, all combinations of these ingredients are not suitable for the purposes of this invention. In order to obtain the advantages of this invention, the solvent must contain at least 5% by volume of both ingredients. This limitation is imposed on the mixture by reason of the fact that as the composition of the mixture approaches either pure phenyl ethanol amine or diethylene glycol, the solvent mixture approaches the properties of the pure compounds. On the other hand, a mixture containing at least 5% of both ingredients exhibits unexpected and surprising improvements in solvent behavior, both as to selectivity for the aromatic compounds and as to the solubility of such compounds in the solvent, which cannot be predicted from the properties of either of the pure ingredients. It has been found that the inclusion in the solvent mixture of small amounts of water, i. e., below about 10% by volume, will not have a detrimental effect on the solvent and in some instances will produce beneficial effects.

The procedure to be followed in carrying out the method of this invention will be better understood by reference to Figure 1 of the attached patent drawing. A hydrocarbon distillate is conveyed by means of a pump 10 and conduit 11 to a packed extraction tower 12. Any of the conventional tower packings may be employed in tower 12. While the extraction zone is shown on the drawing as the tower 12, any of the conventional equipment employing one or more theoretical extraction stages which is available for liquid-liquid extraction may be employed, for example, a centrifugal extractor. The light hydrocarbon distillate is contacted in the extraction zone with a mixture of phenyl ethanol amine and diethylene glycol which is introduced into the extraction zone by means of the pump 13 and conduit 14. A raffinate which is predominantly paraffinic in nature is produced in the extraction zone and leaves the tower 12 by means of the conduit 15. The final disposition of the raffinate is not important to this invention, but it may be recycled to the catalytic reforming operation. The extract which is a solution of hydrocarbon richer in aromatics and solvent is conveyed from the extraction zone through the conduits 16a and 16b to the fractionator 17. The fractionator 17 is equipped with the usual re-boiler 19 which is connected to the tower by means of the conduit 20. Stripping steam may be added to the fractionator 17, if desired, by means of the conduit 18. The extract is separated into two fractions within the fractionator 17. One fraction

is a hydrocarbon stream which is enriched in aromatics and this fraction leaves the fractionating zone by means of the conduit 21. The other fraction is the mixture of phenyl ethanol amine and diethylene glycol, and this mixture is returned to the extractor 12 by means of the conduits 22a and 22b, pump 13 and conduit 14. The fractionated solvent mixture should be cooled before return to the extractor 12 and the cooling may be conveniently accomplished in heat exchanger 23 where the heat extracted is employed to heat the extract phase removed from extractor 12. The fractionator 17 may be any of the conventional fractionating apparatus such as, for example, a bubble cap tower. The fractionation zone may be operated either under pressure or under vacuum. In the latter instance, conventional equipment (not shown) is employed to produce the vacuum in a manner which is well understood in the art.

While in the above description of this process, fractionation has been disclosed as a method whereby the solvent mixture may be recovered from the extract, the invention broadly encompasses any method of solvent recovery. For example, fractional crystallization might be utilized.

A number of experimental runs were made in order to illustrate the improvements obtainable by the method of this invention. All of the extractions reported herein were conducted under atmospheric pressure and the procedure shown on the patent drawing and described above was followed. The stock employed in the experimental work was a commercial stock produced by the "Platforming" process, a commercial catalytic reforming process, and it had the properties reported in Table I.

The data obtained in the various experimental runs are reported in Table II. In this table, phenyl ethanol amine and diethylene glycol are designated as PEA and DEG respectively. The solvent to oil ratios reported represent the volume ratio of solvent mixture to hydrocarbon which is introduced to the extraction zone. Octane numbers reported in this table and throughout this specification are the clear F-1 numbers which are obtained by a method well understood in the art. The yields reported represent the volume per cent of the feed which is recovered from the aromatic enriched extract. Table II follows:

TABLE II

Example Number	Solvent Composition, Volume Percent	Extraction Temperature, °F.	Solvent to Oil Ratio	Yield, Volume Percent	Octane Number of Product
1	100% PEA	130	0.43	13.9	96.4
2	100% PEA	130	1.0	26.8	95.5
3	100% PEA	130	2.3	39.0	93.8
4	100% DEG	130	0.1	0.4	103.8
5	100% DEG	130	0.25	0.9	103.8
6	100% DEG	130	0.43	1.6	103.8
7	100% DEG	130	1.0	3.5	103.8
8	100% DEG	130	2.3	4.8	103.8
9	70% PEA-30% DEG	130	0.1	2.1	106.2
10	70% PEA-30% DEG	130	0.43	8.7	104.4
11	70% PEA-30% DEG	130	1.0	13.8	103.5
12	70% PEA-30% DEG	130	2.3	31.2	102.3
13	50% PEA-50% DEG	130	0.1	1.8	105.0
14	50% PEA-50% DEG	130	0.43	9.9	104.0

16	50% PEA-50% DEG	130	2.3	31.8	102.0
17	30% PEA-70% DEG	130	0.1	1.3	104.7
18	30% PEA-70% DEG	130	0.43	4.9	104.0
19	30% PEA-70% DEG	130	1.0	9.4	104.0
20	30% PEA-70% DEG	130	2.3	21.2	103.5
21	50% PEA-50% DEG	200	2.3	37.7	95.1
22	50% PEA-50% DEG	250	2.3	46.4	93.8
23	70% PEA-30% DEG	100	0.43	7.9	100.2
24	70% PEA-30% DEG	100	1.0	16.4	99.4
25	70% PEA-30% DEG	100	2.3	32.3	97.5
26	50% PEA-50% DEG	100	0.43	5.8	101.7
27	50% PEA-50% DEG	100	1.0	12.1	100.6
28	50% PEA-50% DEG	100	2.3	25.5	100.2
29	30% PEA-70% DEG	100	0.43	4.2	103.6
30	30% PEA-70% DEG	100	1.0	9.1	101.2
31	30% PEA-70% DEG	100	2.3	18.6	100.8

The data reported for Examples 1-8 in Table II illustrate the shortcomings and deficiencies of the solvents suggested by the prior art. Examples 1-3 show that when pure phenyl ethanol amine is employed as the solvent, the aromatic content of the product, as indicated by the octane number, is improved, but not to the extent desired. The data reported for Examples 1-3 also illustrate the fact that increasing the solvent to oil ratio does not improve the quality of the product, but on the contrary, as the solvent to oil ratio is increased, the concentration of aromatics in the product tends to approach the concentration of aromatics in the feed.

Examples 4-8 plainly indicate that while diethylene glycol is capable of producing a high quality product in a solvent extraction process, the yield of the product is poor. Extrapolation of this data indicates that commercial yields of products could be obtained with diethylene glycol only if high solvent to oil ratios are employed, i. e., on the order of 6-10:1. One of the principal advantages of our invention is that such high solvent to oil ratios are not required.

From a study of the data reported in Table II, we have concluded that the best mode contemplated by us of carrying out our invention embodies a solvent extraction process carried out according to the procedure described herein above in which the solvent mixture is a 50-50 mixture of phenyl ethanol amine and diethylene glycol and the extraction temperature is 130° F., while the solvent to oil ratio is 2.3:1.

Considering this invention in its broadest aspect, we contemplate employing solvent mixtures consisting essentially of at least 5% by volume of phenyl ethanol amine

and 5% by volume of diethylene glycol. Solvent mixtures containing 50% or less of diethylene glycol are preferred. However, mixtures containing as much as 95% diethylene glycol and only 5% phenyl ethanol amine have been found to offer considerable improvement in the extraction process as compared to the pure diethylene glycol.

The temperature at which the extraction is carried out is not critical so long as a temperature is employed which will result in separable extract and raffinate phases in the extraction step. However, it is preferred to employ temperatures in the range of about 100 to 175° F.

The solvent to oil ratios which may be employed in the method of this invention are likewise not critical. However, low solvent to oil ratios produce lower yields of products whereas high solvent to oil ratios impose handling and separation problems which adversely affect the economics of this process. Accordingly, it is preferred to employ solvent to oil ratios in the range of about 0.25 to about 4.0.

A better understanding of the surprising and unexpected properties of the solvent mixtures of this invention may be had by reference to Figure 2 of the patent drawings. In the graph presented in Figure 2, the solvent rating has been plotted against the composition of the solvent mixture for Examples 3, 8, 12, 16, and 20. The solvent rating is a function of the product yield and increase in aromatic concentration of the product and is obtained by means of the following arbitrary formula:

$$\text{Solvent rating} = \frac{\text{percent yield} \times \text{octane number (product-feed)}}{100}$$

According to this formula, the best solvent will have the highest rating.

The broken line on the graph of Figure 2 represents the rating for mixtures of phenyl ethanol amine and diethylene glycol which would be expected from the solvent rating of the pure components. The solid line represents a curve which was drawn through the data actually obtained in Examples 12, 16 and 20. The surprising improvement in the solvent rating of the mixtures as compared to the rating which might have been predicted from a knowledge of the ratings of the pure ingredients is apparent.

Modifications of the procedure described herein for carrying out the method of this invention will be obvious to those skilled in the art, but this application for Letters Patent is intended to cover all such modifications as would reasonably fall within the scope of the appended claims:

The term "consisting essentially of," as used in the appended claims, is not meant to exclude materials from the solvent mixtures which will not materially alter the properties of such mixtures.

We claim:

1. A method of producing a hydrocarbon mixture enriched in aromatic content from a hydrocarbon feed mixture of lesser aromatic content comprising the step of extracting said feed mixture with a solvent mixture consisting essentially of diethylene glycol and phenyl ethanol amine in which said solvent mixture components are both present in amounts above 5% by volume so as to form a separable extract phase consisting of a mixture of hydrocarbons and solvent, and the step of separating an aromatic enriched hydrocarbon mixture from said extract phase.

2. The method of claim 1 in which said hydrocarbon feed mixture is a catalytically reformed heavy naphtha.

3. A method of producing a hydrocarbon mixture enriched in aromatic content from a hydrocarbon feed mixture of lesser aromatic content comprising the steps of extracting in an extraction zone said feed mixture with a solvent mixture consisting essentially of diethylene glycol and phenyl ethanol amine in which said solvent mixture components are both present in amounts above 5%

by volume so as to form separable extract and raffinate phases, separating said extract phase from said raffinate phase, and fractionating said extract phase so as to separate said solvent mixture from the hydrocarbon mixture contained therein which is enriched in aromatic content.

4. A method of producing a hydrocarbon mixture enriched in aromatic content from a hydrocarbon feed mixture of lesser aromatic content comprising the steps of extracting in an extraction zone said feed mixture with a solvent mixture consisting essentially of diethylene glycol and phenyl ethanol amine in which said solvent mixture components are both present in amounts above 5% by volume so as to form separable extract and raffinate phases, separating said extract phase from said raffinate phase, fractionating said extract phase so as to separate said solvent mixture from the hydrocarbon mixture contained therein which is enriched in aromatic content, and recycling said fractionated solvent mixture to said fractionation zone.

5. A method of producing a hydrocarbon mixture enriched in aromatic content from a hydrocarbon feed mixture of lesser aromatic content comprising the steps of extracting in an extraction zone said feed mixture with a solvent mixture consisting essentially of diethylene glycol and phenyl ethanol amine in which said solvent mixture components are both present in amounts above 5% by volume so as to form separable extract and raffinate phases, removing said extract phase from said extraction zone and adding an appreciable quantity of heat to said extract, fractionating said extract to produce said hydrocarbon mixture enriched in aromatic content and to re-

cover said solvent mixture, cooling said solvent mixture and recycling it to said extraction zone.

6. The method of claim 5 wherein said extract phase is heated and said fractionated solvent mixture is cooled by passing them in heat exchange relation to each other.

7. A method of producing gasoline having an octane number at least above 100 from a gasoline having an octane number of 85, comprising the steps of introducing said 85 octane gasoline into an extraction zone and extracting at a temperature of about 130° F. said 85 octane gasoline with a solvent mixture consisting essentially of approximately equal quantities of diethylene glycol and phenyl ethanol amine, the amount of said solvent mixture in said extraction zone being in the ratio of 2.3 volumes of solvent mixture to 1 volume of said 85 octane gasoline, so as to form separable extract and raffinate phases in said extraction zone, removing said extract phase from said extraction zone and adding an appreciable quantity of heat to said extract phase, fractionating said extract phase to obtain said 100 octane gasoline and said solvent mixture, cooling said fractionated solvent mixture and recycling it to said extraction zone.
